FOLDING STOOL OR CHAIR

Elmer T. Skidmore, Highland Park, Ill.

Application August 29, 1934, Serial No. 741,902

6 Claims. (Cl. 155—139)

The invention relates to folding stools or chairs, and particularly to the type of stool or chair which, when not in use, may be folded compactly so as to save room at a wall, table, bar or other place, and may be quickly and readily pulled out and unfolded into position and be used.

An important object of the invention is to construct a stool or chair which will conveniently fold forward under the overhang of a bar or counter top, under tables, show cases, work benches, and other structures, or fold backward against a wall, partition, or counter, in such a manner as to provide ample and convenient space for standing or walking when the stool or chair is not in use.

One of the important features of the invention is in having one pair of legs of the stool or chair fastened to the floor, bar, or other support, and moving the other pair of legs toward the first mentioned pair of legs to cause the stool or chair to be in a closely folded and compact position, and able to stand upright by itself, unaided, and without leaning against the wall, bar, or other support, and without the liability of being knocked down or dropped back flat on the floor.

Another important feature of the invention is that the stool or chair when folded and arranged to stand uprightly against a wall, bar or other support, is substantially locked in that position and cannot be pulled out, unfolded and put into operative position when an attempt is made to move the stool or chair laterally.

The stool or chair is caused to be folded and locked, or unfolded and unlocked by the employment of various means, including the hinged joints, the stop and locking lugs, the seat plate, the proper length of the legs, and the lift and push, and the lift and pull movements. When one pair of legs of the stool or chair is secured in the hinged joint which in turn is fastened to the floor, or a fixture, a lift and push movement by grasping the back rest will cause the stool or chair to raise and fold in a perpendicular position against the bar or counter, or under the overhang thereof, under the table, or against the wall, the other pair of legs automatically folding in a parallel position with the first mentioned pair of legs and being of sufficient length as to enable them to rest against the floor when folded causing a locking in this position of the stool or chair so that it cannot be pulled or laid down flat on the floor even though it is constructed with a hinged base, and the lift and pull movement while in this position will automatically

unlock, release and unfold the stool or chair out to the proper position for regular use.

One of the objects of the invention is to set a pair of legs of the chair and the back rest substantially straight or perpendicular, allowing any desired back rest to be permanently attached, keeping the back rest in a perpendicular position at all times during the folding operation, and in this way the said legs, with the back rest permanently attached, are still in a perpendicular position and out of the way after being folded.

It is an object of the invention to fasten one pair of legs of the stool or chair in a stationary position closely adjacent the bar, counter, table base, booth partition or wall, or instead of fastening the pair of legs to the floor, it may be fastened, or attached, directly to the bar, counter, table base, booth partition or wall, allowing the stool or chair to fold conveniently and also allowing more space, passageway or room for transportation or walking.

Another feature of the stool or chair is that it is interchangeable for either counter, table or booth stools or chairs, but utilizes the same folding features regardless of the heights required for the various sizes and heights of bars, counters, tables, booths, benches, etc.

The stool or chair of the invention may be made from various materials such as iron, aluminum, steel or other metals or it may be made of wood. It will also be obvious that the stool or chair may employ various types of stool or chair seats and backs.

The stool or chair of the invention, because of its special folding and unfolding features is particularly useful for bar rooms, beer parlors, restaurants, ice cream parlors, cafeterias, hotels, department stores, retail stores, banks, at bookkeepers', engineers' and draftsmen's desks or tables, and in other places.

The invention will best be understood by reference to the accompanying drawings, wherein the structure of the invention and modifications are shown, it being understood that I do not limit myself to the exact construction shown and illustrated, but in the claims hereinafter set forth intend to cover all variations and modifications thereof.

In the drawings—

Figure 1 is a side elevational view of a stool or chair in unfolded condition showing the back rest and rear legs in substantially vertical planes, the front legs being fastened to a single bar or plate which is fastened to the floor;

Figure 2 is a front elevational view of the

stool or chair shown in Fig. 1, showing the pair of diverging front legs;

Figure 3 shows a side elevation of the stool in folded condition, with the same stool in unfolded condition shown in dotted lines; and also shows the vertical and lateral movements required to raise and move the stool while in locked and folded position to the unlocked and unfolded position;

10 Figure 4 is a bottom plan view of the seat of the stool and the connecting rods and method of fastening the legs to the seat as shown on the line 4—4 of Fig. 1;

15 Figure 5 is a cross sectional view of the stool seat on the line 5—5 of Fig. 4;

15 Figure 6 is a side elevational view of another form of stool or chair employing the features of the stool or chair shown in Figs. 1 to 5 inclusive, but employing a converging form of front legs to a smaller fastener than is employed in the stool in Figs. 1 to 5 inclusive;

20 Figure 7 is a side elevational view of the stool of Fig. 6 in folded and upright position;

25 Figure 8 is a front elevational view of the stool shown in Figs. 6 and 7;

25 Figure 9 shows a form of bar or wall vertical fastener for the front legs of the stool;

30 Figure 10 is a detailed view of the rear leg and back connecting rods, the rods being shown in section, as shown on the line 10—10 of Fig. 6;

30 Figure 11 is a detailed cross sectional view of the lower rod connecting the rear legs with the back, on the line 11—11 of Fig. 6;

35 Figure 12 is a detailed view of the floor support for the front legs shown on the line 12—12 of Fig. 7 and 12—12 of Fig. 13;

40 Figure 13 is a detailed view of the front leg floor support showing the floor support lug with the lower end of the front leg in elevation and the end of the leg against the lug in dotted lines;

45 Figure 14 is a side elevational view of a table having a plurality of stools or chairs such as are illustrated in Figs. 6, 7 and 8 placed at the table in unfolded and also folded positions showing the floor supports secured to plates which are fastened to the base of the table;

50 Figure 15 is a detailed view of the table base plate and chair support on the line 15—15 of Fig. 14;

50 Figure 16 is a view of the table base, plate and stool supports shown on the line 16—16 of Fig. 15;

55 Figure 17 is a side elevational view of another modified form of stool in unfolded condition, having a sliding arrangement in the back rest, and showing a floor fastener secured to the rear legs;

60 Figure 18 is a side elevational view of the stool of Fig. 17 in folded condition showing the rear legs and back in substantial vertical alignment;

60 Figure 19 is a front elevational view of the stool, shown in Figs. 17 and 18;

65 Figure 20 is a bottom plan view of the stool seat and back and connecting mechanism as shown on the line 20—20 of Fig. 17;

65 Figure 21 is a detailed view of the slide bar which operates in the slide of the stool of Figs. 17, 18 and 19; and

70 Figure 22 is a top plan view of the brace plate and its connections as shown on line 22—22 of Fig. 17;

70 Figure 23 is a top plan view of the floor plate shown in Figures 1, 2 and 3.

Like parts throughout the various views are given the same reference characters.

75 The stool or chair shown in Figs. 1 to 5, both

inclusive, comprises the seat 25 which is supported by the front legs 26 and 27 which diverge from the seat and are secured to the front supporting plate 28, which in turn is secured to the floor.

5 The upper ends of the front legs 26 and 27 are secured to the supporting U-shaped seat plate 29. Rear legs 30 and 31 also have their upper ends secured to the U-shaped seat plate 29. The front and rear legs are braced by the pivoted 10 brace plate 32. The back rest 33 is secured to the rear legs 30 and 31 by means of three spaced rods or bolts 34, 35 and 36. The back rest 33 of the stool is provided with horizontal strengthening cross bars 37 and 37a and a vertical intermediate strengthening bar 38. The front legs 26 and 27 are provided with the lower foot rest 39 which also acts as a cross brace, and the upper cross brace 40. The rear legs 30 and 31 are provided with the lower cross brace 41 and the 20 upper cross brace 42.

15 In the form of stool or chair shown the back braces 37 and 38 are formed integral with the back 33. The front leg foot rest and brace 39 and brace 40, and the back leg braces 41 and 42 25 are integral with their respective front legs 26, 27 and back legs 30, 31. The cross brace 32 is pivotally mounted on upper 30 pivot rod 43 and lower pivot rod 44, the ends of which are permanently riveted in their respective legs. The end portions of the pivot rods 43 and 44 pass through the plurality of corner eyelets 45 of the brace 32.

35 Bolts 34, 35, and 36 which pass through the rear legs 30 and 31 and the depending ends 33a and 33b of the back and the cross bar 37a, are provided with protecting and strengthening sleeves 46, 47 and 48, which maintain the stool 40 or chair back in spaced relation to the back legs. The bolts and sleeves are made of such lengths that the stool or chair back shall be in such spaced relation to the back legs that the user may sit on the seat with comfort. It will be 45 noticed that there is a 3-point connection formed by the bolts and sleeves connecting the back legs with the back rest. It will also be noted that any form of back rest can be readily secured to the stool or chair by means of the bolts 34, 35 50 and 36.

55 The plate 28, to which the lower ends of the legs 26 and 27 are secured, is provided with the integral fastening lugs 49 and 50. Bolts and nuts 51 and 52 pass through apertures in the lugs 49 55 and 50 and the adjacent lower ends of the legs 26 and 27. Stop and locking lugs 53 and 54 are also integrally formed in the plate 28, being placed in the rear portion of the plate 28. The plate 28 is secured to the floor by means of the bolts and 60 nuts 55 and 56.

65 The U-shaped seat plate 29 which connects the seat with the top portion of the legs 26, 27 and 30, 31 is secured to the under face of the seat frame 57. As more clearly shown in Fig. 4, the seat 65 frame is formed with integral cross plates 58 and 59 which extend from the peripheral part of the seat frame 57.

70 At the intersection of the cross plates 58 and 59 is the boss 60. Additional bosses or ribs 60a, 70 60b and 60c on the cross arms or plates 58 and 59 are formed to assist in supporting the U-shaped plate 29. These additional bosses extend from the central boss 60 and the plate 29 rests against them.

The U-shaped seat plate 29, the upper end portions of the legs 26 and 27 and the cross brace 40 are apertured to receive the pivot rod 61. The upper ends of the rear legs 30 and 31 and the rear portion of the U-shaped plate 29 are apertured to receive the pivot rod 62. A third or intermediate rod 63 extends through both sides of the U-shaped frame or plate 29 and acts as a stop for the top ends of the front legs 26 and 27. The U-shaped plate 29 is secured by bolts and nuts 64, 65 and 66 which hold it firmly against the ribs of seat frame 57. The upper ends of the four legs are pivotally mounted on the pivot rods 61 and 62 secured and held in the downwardly extending ears of the seat plate 29.

By reference to Fig. 3 the operation of the stool or chair will be readily understood. In the left-hand portion of the figure, the bar or counter 67 is shown with the stool folded and placed close to its wall 68 as far as possible in view of the fastening of the support plate 28 and the stop and locking lug 54. In this figure the numerals 1, 2 and 3 will be seen in various places to more clearly show the operation of the stool. Numerals 1, 1, 1, 1, indicate the lifting or raising movement of the various parts where the numerals appear, which movement is required in order to unlock the stool from its locked position as shown in the full lines of the figure.

Numerals 2, 2, indicate the backward pull movement of the rear legs when the stool is to be unfolded, and the uppermost numeral 3 in the figure indicates the movement of the unfolded seat. The lower numeral 3 indicates the movement of the brace 32 in the portion of the figure showing the completely unfolded stool shown in dotted lines.

When the stool or chair is in the folded position as shown in the left-hand portion of Fig. 3, it is counterbalanced and locked in such a way that with the aid of the support at the plate 28, and particularly with the assistance of the supporting and locking lugs 53 and 54, it will stand upright in position without assistance. The lower portion of the legs 30 and 31 touch the floor and the lower portion of the legs 26 and 27 are stopped by the locking lugs 53 and 54 in such a way that the whole stool cannot fall toward the bar or wall 68, or away from it. It is, of course, essential that the stool shall not tip over and rest against the bar wall 68 since it would mar the finish thereof, and, obviously, the stool or chair must not be permitted to fall and lie on the floor. It will therefore be seen that in order to release the folded stool or chair from its locked position to have it in unfolded position for use, it is first necessary to raise the back rest 33 carrying the legs 30 and 31, a slight distance from the floor, thus releasing them and moving them along the arc indicated by the numeral 2 in the left-hand portion of Fig. 3.

It will be understood that the distances indicated by the numerals 1, 1, 1, 1, are exaggerated for the purpose of illustration. The parts do not move as far as indicated in the figure, but they do move sufficiently to release them from the locked position. When the back of the stool or chair and the legs are moved on the pivots 62 and 61, the seat 25 and the seat frame 57 assume a horizontal position as shown in the dotted lines in the right-hand portion of Fig. 3. The brace 32 pivoted on the pivot rods 43 and 44 assume the position also shown in the dotted line portion of the figure. After the stool is placed in the position indicated by the dotted lines in the right-

hand portion of Fig. 3, it will be seen that the rear legs 30 and 31 are in a vertical position and that the back of the stool is also in a vertical position, and the front legs 26 and 27 are angularly disposed with relation to the rear legs; whereas in the full line illustration at the left-hand portion of the figure both the front and rear pairs of legs are in a vertical position with the back of the chair also in a vertical position. 5

The stool or chair which has been referred to in the foregoing detailed description has relatively long legs 26, 27 and 30, 31 and is particularly adapted for use at a bar or relatively high counter, and for that reason requires the wide form of supporting plate 28 to take the diverging end portions of the legs of the stool. Foot rest 39 is required in this form of stool to enable the user to rest his feet thereon, since normally they are away from the floor for some distance.

In the form of stool or chair shown in Figs. 6, 20 7 and 8 substantially the same general construction of legs, back and U-shaped plate are used. The U-shaped plate 29, however, is placed directly against the bottom of the seat portion 25. The seat does not have the frame 57, although it could be employed. The front legs and the back legs are shortened to a considerable extent so that the stool or chair may be used at a relatively low counter or bar, or may be used at a table where the feet of the user may rest on the floor; therefore there is no foot rest between the legs 26 and 27 as is the case in the stool of Figs. 1, 2, and 3. Since the front legs 26 and 27 converge and are relatively narrower at their base, the foot supporting plate is different in construction from that of the plate 28, but the principle of operation involving both plates is the same. 30 35

The supporting plate 69 is formed with the integral lugs 70 and 71 through which the pivot rod 72 extends. The pivot rod not only extends 40 through the lugs 70 and 71 but through the end portions of the front legs 26 and 27. The front legs 26 and 27 pivot in the support 69 in the same manner in which they pivot in the elongated plate 28 of the first mentioned stool. The operation of the stool of Figs. 6, 7 and 8 is identical with that of the stool of Figs. 1, 2 and 3.

In order to secure the lock and counterbalance relation of the parts of this stool or chair, it will be seen that the lower portion of the legs 26 and 50 27 move toward and away from the stop lug 73 in identically the same manner as they move toward and away from the stop lugs 53 and 54 as shown in Figs. 1, 2 and 3.

This relation of the ends of the legs 26 and 27 55 with the support 69 having the lugs 70, 71 and 73 is further shown in Figs. 6, 7 and 13 of the drawings. A detail of the floor support is shown in Fig. 12 of the drawings.

The wall form of support for the end portions 60 of the front legs, as distinguished from the support which is secured to the floor, is shown in Fig. 9. A wall plate 74 is attached to the bar wall 68 by means of the bolts 75 and 76. A right angled portion 77 formed integrally with the wall 65 plate 74 extends therefrom near the floor. The end portions of the legs 26 and 27 are pivotally secured to the extending portion 77 by means of the pivot 78.

Detailed views of the form of bolts 34 and 36 70 and the sleeves 46 and 48 and their method of securing is shown in Figs. 10 and 11.

Referring to Figs. 14, 15 and 16, there is shown a table 79 with stools or chairs like that of Figs. 6, 7 and 8 placed around it, together with illus- 75

trations showing the details of connections of the table plate with the front legs of the stools. The table standard 80 is provided with the base 81 which has a plurality of supporting plates 82 secured thereto. As shown, there are supporting plates 82 on each side of the table base 81. They are secured in the table base by any suitable means, as by screws. The front leg supports 69 are suitable secured, as by bolts, to the projecting portions of the plate 82. The same form of supporting plate with the pivot joints and lugs as shown in Figs. 12 and 13, are employed in this construction.

It will be seen, as illustrated in Fig. 14, that the stools or chairs surrounding the table 79 are each secured to a base plate 82, which in turn is permanently secured to the table base 81, and that when the stools are in their folded condition they stand underneath the table top 83, and the table with the four stools attached thereto, as described above, may be bodily lifted and transported as a single unit from place to place as may be desired. This is a very important point in connection with the use and transportation of tables and stools in restaurants, dining rooms, bar rooms and the like.

With regard to the stool or chair as shown in Figs. 17 to 22, inclusive, the construction is similar in some respects to the stools and chairs heretofore described, but because the stool is adapted to be used in a different situation than the stools heretofore described, the floor support is secured to the lower end portion of the rear legs instead of the lower end portion of the front legs. This will be particularly noted in Fig. 17. This stool is especially well adapted for use in booths used in ice cream parlors, breakfast nooks and the like. Further modification with reference to a sliding feature is also shown in the stool illustrated in Figs. 17 to 22, inclusive.

In the stool or chair of Figs. 17 to 22 inclusive, the U-shaped seat plate 84 is identical with the U-shaped seat plate 29 of the stools heretofore referred to, but its position is reversed so that the front legs 85 and 86 are vertically disposed beneath the seat 87, and the rear legs 88 and 89 are angularly disposed with relation to the front legs 85 and 86 so that the pairs of legs are in the reverse position with respect to the seat from those in the stools heretofore referred to.

The pivot rods 90 and 91 function in the same manner as the pivot rods 61 and 62, and the stop rod 92 functions in the same manner as the stop rod 63 shown in Figs. 1 and 2. The leg brace 93 is pivotally secured at 94 to the front legs 85 and 86 and at 95 to the rear legs 88 and 89. The pivot pin 95 is longer, however, than the pivot pin 44 shown in Fig. 2. This pivot pin 95 being long, has ends which project beyond the rear legs 88 and 89 as at 96 and 97, to receive the lower end portions 98 and 99 of the stool back 100 as shown in detail in Fig. 22.

Another feature of difference between the stool or chair of Figs. 17 and 22 inclusive, from the ones heretofore described, is in the sliding feature associated with the seat and the stool back. The stool back 100 has secured to it the horizontal cross bar 101 and the horizontal cross bar 102. Behind the vertical bar 103 is the slide bar 104. This bar 104 has inwardly extending securing and spacing portions at its top and bottom whereby a slide groove 105 is formed (see Fig. 17).

Extending from the slide bar 104 to a U-shaped support 106, which is secured to the U-shaped seat plate 84, are the pair of bars or plates 107

and 108. These plates 107 and 108 are each securely and firmly riveted to the U-shaped support 106. They are also provided with the spacer bolt 109 and the fixed pin 110. The fixed pin 110 extends through both of the spaced bars 107 and 108 into the slide-way 105.

When the stool is in its unfolded condition, with the seat in horizontal position, the sliding groove pin 110 is adjacent the bottom of the slide-way 105. When the stool is folded, the outer ends 10 of bars 107 and 108 carrying the pin 110 upwardly in the slide-way 105 are moved upwardly toward the top of the slide-way 105. The stool is then in the position illustrated in Fig. 18.

It will be obvious that a good fit of the top 15 portions of the rear legs 88 and 89 against the stop pin 92 may be obtained by providing the shoulders or cut-outs 111. The U-shaped support 84 is secured directly to the seat 87 without the interposition of the seat frame, such as the 20 seat frame 57, with its special construction as shown in Fig. 4.

It will be seen that when it is in its folded position the stool or chair may stand adjacent a wall or in a booth in a little different situation 25 from the manner in which the stools of Figs. 3 and 7 stand.

In other words, the stools are provided with the foot supports on either the front or the rear foot portions to enable them to be placed in the 30 various situations required in commercial practice, whether towards or away from bars, counters, walls, tables and the like.

What I desire to claim and secure by Letters Patent is:

1. In a folding stool or chair, a pair of front legs, a pair of rear legs, the top portions of each of said legs being pivotally secured at four widely separated places to a channel or inverted U-shaped seat plate, a seat surmounting said plate, 40 a stop rod, said stop rod extending from one side of said U-shaped seat plate to the other side of said seat plate, a wide flat brace between said pairs of front and rear legs pivotally mounted at its corners to said pairs of front and rear legs, 45 said stop rod and said wide flat brace acting to make said stool or chair more rigid and providing against lateral movement, and a back rest fastened to said pair of rear legs, said back rest being spaced far enough from said seat to furnish a comfortable position to the user, said back rest being held in spaced relationship to said seat by sleeves mounted on three bolts arranged trinangularly.

2. In a folding stool or chair, the combination 55 of a channel or inverted U-shaped seat plate, said channel plate having two downwardly extending sides, a pair of front legs, a pair of rear legs, each of said pairs of legs being pivotally secured to the downturned sides of said channel 60 plate at four widely separated places, a seat, a plate interposed between said seat and said channel or U-shaped seat plate, said plate being provided with bosses to support said U-shaped plate, a stop rod, said stop rod being secured to the U- 65 shaped plate, said stop rod acting as a base for said U-shaped plate in addition to acting as a stop, said stop rod being placed intermediate the top portions of said front and back legs, the stop rod and the pivots of the top leg portions 70 extending into and through said downturned ears of said U-shaped plate, each of said stop rod and pivots being in a different horizontal plane from the others.

3. In a folding stool or chair the combination 75

of a pair of front legs, a pair of rear legs, the top portions of each of said legs being pivotally secured at four widely separated places to a channel or inverted U-shaped seat plate, a stop rod, 5 said stop rod and said pivots passing into and through the downwardly extending ears of said seat plate, said seat plate with its downwardly extending ears and said stop rod and pivots acting as a brace for said combined structure, said stop rod being placed intermediate the top portions of said front and rear legs, said pivots and said stop rod each being in a different horizontal plane from the other, a wide flat brace secured at each of its four corners to 10 said pairs of front and rear legs, said flat brace being pivotally mounted on each of said legs to hold the four legs against lateral movement and a back rest spaced from the top portions of said rear legs, said back rest being held in spaced 15 relationship thereto by three supports in a triangular relation.

4. In a folding stool or chair, a pair of front legs, a pair of rear legs, a channel or inverted U-shaped seat plate, the top portions of each of the legs of said pairs of legs being pivotally connected to the downwardly extending portions of said seat plate, a stop rod, said stop rod being secured to said plate intermediate the top portions of said front and back legs, said stop rod 20 acting as a stop for the top portions of said front legs, said pivots and stop rod being in different horizontal planes, a wide flat brace secured to each of said legs at its four corners, a support attached to the front pair of legs, said support being adapted to be secured to a floor, wall or other support to prevent removal of said stool, said support being provided with lugs, said lugs being parallel to the pivots of said legs and in proximity to an edge of each of said 25 pair of front legs, a seat secured to said seat plate, said pair of front legs being longer than said pair of rear legs, said pair of front legs extending from the forward portion of said inverted U-shaped plate, said pair of rear legs extending from the rear portion of said U-shaped plate, the ends of said front legs contacting with said support on one side of said lugs and the lower end of said rear legs contacting with the floor and when the stool is in closed position 30 contacting with the floor adjacent said support and on the opposite side of said lugs serving to maintain said stool in a locked, upright and standing position when said pairs of legs are pushed and folded together.

5. In a folding stool or chair, a pair of front legs, a pair of rear legs, a channel or inverted U-shaped seat plate, the top portions of each of the legs of said pairs of legs being pivotally connected to the downwardly extending portions of said seat plate, a stop rod, said stop rod being secured to said plate intermediate the top portions of said front and back legs, said stop rod 35 acting as a stop for the top portions of said front legs, said pivots and stop rod being in different horizontal planes, a wide flat brace secured to

each of said legs at its four corners, a support attached to the front pair of legs, said support being adapted to be secured to a floor, wall or other support to prevent removal of said stool, said support being provided with lugs, said lugs being parallel to the pivots of said legs and in proximity to an edge of each of said pair of front legs, a seat secured to said seat plate, said pair of front legs being longer than said pair of rear legs, said pair of front legs extending from the forward portion of said inverted U-shaped plate, said pair of rear legs extending from the rear portion of said U-shaped plate, the ends of said front legs contacting with said support on one side of said lugs and the lower ends of said rear legs contacting with the floor and when the stool is in closed position contacting with the floor adjacent said support and on the opposite side of said lugs serving to maintain said stool in a locked, upright and standing position when said pairs of legs are pushed and folded together but permitting release from its locked, upright and standing position by an upward lift of said stool whereupon the stool may be pulled out and unfolded to be used.

6. In a folding stool or chair, a pair of front legs, a pair of rear legs, a channel or inverted U-shaped seat plate, the top portions of each of the legs of said pairs of legs being pivotally connected to the downwardly extending portions of said seat plate, a stop rod, said stop rod being secured to said plate intermediate the top portions of said front and back legs, said stop rod acting as a stop for the top portions of said front legs, said pivots and stop rod being in different horizontal planes, a wide flat brace secured to each of said legs at its four corners, a support attached to the front pair of legs, said support being adapted to be secured to a floor, wall or other support to prevent removal of said stool, said support being provided with lugs, said lugs being parallel to the pivots of said legs and in proximity to an edge of each of said pair of front legs, a seat secured to said seat plate, said pair of front legs being longer than said pair of rear legs, said pair of front legs extending from the forward portion of said inverted U-shaped plate, said pair of rear legs extending from the rear portion of said U-shaped plate, the ends of said front legs contacting with said support on one side of said lugs and the lower end of said rear legs contacting with the floor and when the stool is in closed position contacting with the floor adjacent said support and on the opposite side of said lugs serving to maintain said stool in a locked, upright and standing position when said pairs of legs are pushed and folded together, said support also being provided with additional lugs which are transverse to said first mentioned lugs and immediately adjacent to said first mentioned lugs, apertures extending through said transverse lugs to receive bolts to hold the bottom portions of said front legs.
